Application July 30, 1934, Serial No. 737,653

10 Claims. (Cl. 204—5)

My invention relates to the electrolytic pickling of metal objects in general, but more particularly, though not exclusively, to ferrous sheet material, by which term I intend to include all sheet material such as that known to the trade by the technical terms "strip sheet", "strip", "sheets", "plates", etc., it having been found in practice that by passing an electric current through the pickling solution provided for pickling the metal object the pickling operation is accelerated with the manifest advantages.

Heretofore, so far as I am aware, the only use made of electric current for accelerating the pickling operation, has involved the use of direct current introduced into the material to be pickled by some contact means whereby the material itself became one of the electrodes, which procedure, while presenting certain advantages over non-electrolytic pickling, presents disadvantages and limitations which it is one of my objects to overcome.

Broadly stated, my invention, as to one phase thereof, contemplates the use of alternating current for effecting the electrolytic action, and as to another phase thereof, the application of the current, either alternating current or direct current, to the pickling bath without direct contact between the metal of either electrode and the metal object to be pickled.

30. Referring to the accompanying drawings:

Figure 1 represents by a view in side elevation and of diagrammatic nature, apparatus embodying my invention and by which my improved method may be practiced in the pickling of ferrous sheet material, the portion of the apparatus shown at the lower end of the sheet of drawings representing a continuation of the portion thereof located at the upper end of the sheet.

Figure 2 is a view in side elevation of approximately one-half of one of the similar electrolytic pickling tanks of Fig. 1.

Figure 3 is a similar view of the remainder of the tank of Fig. 2.

Figure 4 is an enlarged plan view of a portion of the structure shown in Fig. 2.

Figure 5 is a similar view of the remainder of the structure shown in Fig. 2.

Figure 6 is an enlarged longitudinal sectional view of the structure shown in Fig. 4, the section being taken at the line 6 on Fig. 4 and viewed in the direction of the arrow.

Figure 7 is an enlarged longitudinal sectional view of the portion of the apparatus shown in Fig. 5, the section being taken at the line 7 on Fig. 5 and viewed in the direction of the arrow.

Figure 8 is an enlarged cross sectional view, through one of the similar electrolytic pickling tanks, the section being taken at the irregular line 8—8 on Fig. 2 and viewed in the direction of the arrows.

Figure 9 is a diagrammatic view of a series of two electrolytic pickling tanks showing the circuit connections between the electrodes thereof and a source of supply of three-phase alternating current.

Figure 10 is a diagrammatic view of a series of three electrolytic pickling tanks showing the circuit connections between the electrodes thereof and a source of supply of three-phase alternating current.

Figure 11 is a diagrammatic view of one of the electrolytic pickling tanks showing the circuit connections between the electrodes therein and a source of supply of single phase alternating current.

Figure 12 is a diagrammatic view of a series of two electrolytic pickling tanks and apparatus for supplying direct current to the electrodes thereof.

Figure 13 is a view in longitudinal sectional elevation of a modification of the apparatus of Figs. 1 to 8, inclusive, and of a construction suitable for simultaneously batch pickling large numbers of sheets of lengths not in excess of the length of the tank, the section being taken at the line 13 on Fig. 14 and viewed in the direction of the arrows; and

Figure 14, a section taken at the line 14 on Fig. 13 and viewed in the direction of the arrow.

Referring to Figs. 1 to 8, inclusive, the particular apparatus shown therein and provided for the pickling of relatively long lengths of sheet material, such as ferrous sheet material, of relatively small cross section and relatively great widths commonly supplied in coiled condition on reels and which may be stitched together at their ends to render the strip continuous, comprises a pair of pinch rolls 15 which operate to feed the strip of sheet material to be pickled and represented at 16, to the pickling tanks 17, 18, 19 and 20, shown as four in number and arranged in series with rolls 21 at the ends of the series of tanks and between each tank for supporting the strip 16 in looped condition in each tank, the tanks 17—20 containing any suitable pickling solution, such as any of the acid solutions commonly used in the pickling of the kind of sheet material to be operated on.

Beyond the pickling tanks are a cold water tank 22, for rinsing the acid from the strip, and a hot

water tank 23 for heating and further washing the strip, rollers 24 extending into the tanks 22 and 23 and rollers 25 and 26 located, respectively, between the tanks 22 and 23 and adjacent the discharge end of the tank 23, serving to guide the strip 16 for movement through the liquid in these tanks.

Beyond the tank 23 are pinch rolls 27 for drawing the strip through the tanks and feeding it to a shearing mechanism 28 for cutting out the material at which the stitches between the strips were made.

Beyond the shearing mechanism 28 is oiler mechanism 29 for oiling the strip if found to be necessary or desirable, the strip in accordance with common practice being again wound into coiled condition by the coiling means represented generally at 30.

In the particular illustrated apparatus provision is made for the electrolytic pickling in two tanks only, namely, tanks 18 and 19, but as will be readily understood the number of tanks in which such pickling is effected may be greater or less than those illustrated.

As both tanks 18 and 19 and the electrolytic pickling apparatus of each is of the same construction, the following description, directed to tank 18 and its equipment, will suffice.

The tank 18 is formed of a trough-like shell 31 preferably of sheet steel, the inner surface of which is lined with any suitable material, such as porcelain tile represented at 32, with an interposed current-insulating sheet-lining 33, as for example, of vulcanized rubber, between the shell 31 and lining 32.

The body of the tank thus formed and in which the pickling bath is located is provided with a cover portion represented generally at 34 and shown as formed of a metal frame 35 at which the cover rests on the body of the tank and comprising side girders 36 and cross beams 37 secured thereto and sheathed with current-insulating material; a plate portion 38 secured to the frame 35 and formed of metal sheeting 39 sheathed with current-insulating material; and a series of end-frames 40 and two intermediate frames 41, superposed on, and secured to, the plate portion 38. The end frames 40 are shown as formed of side, end, and cross angle bars 42, 43 and 44, respectively, and the intermediate frames 41 are shown as formed of side and end angle bars 45 and 46, respectively, hooks 47, by which to lift the cover and the parts carried thereby, as for example by a crane, being carried by the side angle bars 42 and 45.

The cover 34 is also shown as provided midway between its ends with a chamber 48 opening downwardly into the tank 18 and connected with a pipe 49 through which fumes rising from the pickling bath may be drawn from the tank.

The ends of the cover 34 incline upwardly in spaced relation to the end-walls of the body of the tank as shown in Fig. 6, to present openings to receive the strip 16.

Located in the bottom of the tank 18 beneath, and in spaced relation to, the strip 16 to be pickled, and extending lengthwise of the tank and submerged in the pickling bath are two groups, respectively, of plate electrodes 50, 50^a, 50^b, 51, 51^a and 51^b, which are spaced apart in end-to-end relation, are of the same length and of a width greater than that of the strip 16 to be pickled, these two groups of electrodes being connected with buss-bars 50^c and 51^c, respectively, by means of strip-leads 50^d and 51^d which

lead outwardly through channels in the side walls of the tank 18, as represented at 18^a.

The electrodes 50, 50^a, 50^b, 51, 51^a and 51^b are supported on stoneware blocks 52, having reduced end-portions 53, which extend upwardly through openings in these electrodes to a position in which they serve to prevent the strip 16, in its travel through the tank, from contacting with the electrodes.

Located in the tank 18 directly above the electrodes 50, 50^a, 50^b, and 51, 51^a and 51^b, respectively, and in spaced flatwise-opposed relation thereto and to the strip 16 are two groups, respectively, of plate electrodes 54, 55, 56, 57, 58 and 59, which are spaced apart in end-to-end relation, extend lengthwise of the tank, and are immersed in the pickling bath, each electrode 54-59 being preferably composed of a metal plate 60, as for example, of copper encased in a lead sheathing 61, the end electrodes 54 and 59 carrying depending blocks 62 of insulating material, as for example, of stoneware, as represented of the electrode 54, to insure against contact of the strip 16 with the metal of these electrodes.

In the particular illustrated apparatus, the electrodes 54-59, inclusive, are mounted to be movable vertically in the tank for adjustment from the operative position shown in Figs. 6, 7 and 8, in which they extend into the pickling bath, into such a position above the bath as to permit the strip 16 when drawn taut to be wholly above the pickling bath, and avoid undue eating away of the strip by the bath in the event of the shutting down of the tanks. Thus the re-threading of a strip to the tanks after each shut down which would be required if the strip remained immersed in the bath due to the destruction of the strip by the bath, is rendered unnecessary.

The mounting and adjusting means for this purpose comprise rods 63 sheathed with acid-resisting material 64 connected with the plates 60 of the electrodes 54-59, inclusive, each of these electrodes being shown as carried by the four of the rods 63, which are vertically slidable in insulated bushings 34^a in the cover 34 and are connected above the cover with current leads hereinafter referred to and forming portions of the electrical circuit by which the electrolytic action is effected.

The upper ends of the rods 63 are pivotally connected by bolts 65 with the lower ends of rack bars 66 from which they are electrically insulated by fiber bushings and washers on the bolts. The rack bars 66 are vertically slidable in guide-ways 67 in heads 68 carried by supplemental frames 69 and 70 secured to the frames 40 and 41 respectively, the racks on the rods 66 meshing with pinions 71 secured to cross-shafts 72 journaled in the heads 68.

One of the shafts 72 carrying the pinions 71 for the electrodes 54 and 55 is connected through suitable speed-reduction mechanism 73 with an actuating hand-wheel 74 and the others of these shafts are connected together for simultaneous rotation by sprockets 75 and sprocket-chains 76.

Those of the shafts 72 carrying the pinions 71 for the electrodes 56 and 57 are also connected together by sprockets and sprocket-chains, as above referred to, those shown being represented at 77 and 78, and power for rotating these shafts applied to one thereof as by an actuating hand-wheel 79 and interposed speed-reduction mechanism 80. Likewise those of the shafts 72 carrying the pinions 71 for the electrodes 58 and 59

59 are connected together by sprockets and sprocket-chains, those shown being represented at 81 and 82, respectively, and power for rotating these shafts applied thereto through an actuating hand-wheel 83 with interposed speed-reduction mechanism 84.

10 The end electrodes 54 and 59 are shown as provided with additional guide means to insure against such binding of these electrodes as would interfere with the desired freedom of vertical adjustment thereof, should the strip 16 be drawn taut against them, these additional guide means being shown as comprising channel bars 85 depending from certain of the cross beams 31 at 15 opposite sides of the tank and guidingly receiving projections 86 extending from the side edges of these electrodes.

20 As will be understood, high amperage low voltage current, as for example in the order of 20,000 amperes at about 9 to 15 volts, imposed on the vertically spaced electrodes, causes the current to pass through the pickling bath and strip 16 thereby accelerating the action of the bath on the strip and greatly reducing the time required 25 for effecting the desired pickling of the strip, over that required where no electrolytic action is produced, thus permitting of the relatively rapid movement of the strip through the apparatus.

25 As stated above, one phase of my invention 30 relates to the feature of interposing the metal object to be pickled between, and in spaced relation to, the opposed electrodes of the electric circuit for producing the electrolytic action, the current used being either alternating current, as 35 for example of 25 or 60 cycles, or direct current. Accordingly, I have illustrated some of the various ways in which the current either alternating current or direct current, may be supplied to the electrodes of the electrolytic pickling tanks.

40 Referring to Fig. 9 which shows a circuit diagram involving the use of alternating current employing a three-phase circuit, the three line current conductors leading from a suitable generator (not shown), for supplying current to such a circuit, are represented at 87, 88 and 89. Two 45 single-phase step-down transformers 90 and 91 are employed, the primary windings 92 and 93 of which are connected to the three leads 87, 88 and 89 and with each other by the current conductor 94 in accordance with common practice. 50 The secondary winding 95 of the transformer 90 is connected, in parallel, by current conductors 96, 97, 98 and 99, with the primary windings 100 and 101 of single-phase step-down transformers 55 102 and 103, respectively, the current conductor 99 connecting with the primary windings 100 and 101 through the medium of tap selector switches 104 and 105, respectively. The secondary winding 106 of the transformer 102 connects, by a 60 current conductor 107, with the lower electrodes 50, 50^a and 50^b of the tank 18 through buss-bars 50^c and, by a current conductor 108 and branch current conductors 109, 110 and 111, with the upper electrodes 54, 55 and 56.

65 The secondary winding 112 of the transformer 103 connects by a current conductor 113 with the lower electrodes 51, 51^a and 51^b of this tank through the buss-bar 51^c, and by a current conductor 114 and branch current conductors 115, 116 and 117 with the electrodes 51, 58 and 59.

70 The secondary winding 118 of transformer 91 is connected, in parallel, with the primary windings 119 and 120 of single-phase transformers 121 and 122, by current conductors 123, 124, 125 and 126 with interposed tap selector switches 127

and 128, as explained of the connections between the secondary winding 95 and the primary windings 100 and 101. The secondary winding 129 of the transformer 121 connects by a current conductor 130 with the lower electrodes 50, 50^a and 50^b of tank 19 through the buss-bar 50^c connecting these electrodes, and by a current conductor 131 and branch current conductors 132, 133 and 134 with the upper electrodes 54, 55 and 56 of this tank. The secondary winding 135 10 of the transformer 122 connects by a current conductor 136 with the lower electrodes 51, 51^a and 51^b of tank 19 through the buss-bar 51^c connecting these electrodes, and by current conductor 137 and branch current conductors 138, 139 and 140 with the upper electrodes 51, 58 and 59 of this tank.

15 The three-phase current is thus converted by the transformers 90 and 91 into two-phase current, the strip 16 itself representing the neutral 20 connection of the two-phase secondary circuit each phase of the two-phase current being connected with the electrodes of a tank so that a substantially balanced load is maintained on the three-phase circuit. 25

20 It may be here stated that the number of tanks in which the electrolytic action is to be produced and the matter of the grouping of electrodes in the tank or tanks as the case may be, may be varied to suit the particular conditions 30 presented. Thus in some cases, the electrolytic action may be confined to a single pickling tank; two as illustrated in Figs. 1-9, inclusive; three as illustrated and further commented upon herein, or even more; the purpose being to provide 35 as many pickling tanks, connected in series, with the electrolytic pickling provided for in certain thereof, as may be necessary to effect the exposing of as much surface to be pickled, to the electrolytic pickling action, as may be required to 40 correspond with the speed of the strip through the tanks.

45 The matter of the dividing of the electrodes into several sections as for example as illustrated in Figs. 1-9, inclusive, and above described, is 45 of advantage as it permits of the utilization of transformers of convenient capacity; provides for the possibility of regulation between the several groups of electrodes in order that the current flow throughout the length of the tank 50 may be balanced; and, in the case of alternating current, reduces excessive voltage losses.

55 The use of three electrolytic pickling tanks in series and supplied with alternating current from a three-phase source is illustrated in Fig. 10 55 wherein the tanks corresponding with tanks 18, 19 and 20, are represented at 18', 19' and 20', each being equipped as described above as to tanks 18 and 19, to electrolytically pickle the strip. 60

65 In this arrangement, the three line current conductors of the three-phase alternating current circuit, supplied from a suitable generator (not shown), are represented at 141, 142 and 143 and, in accordance with common practice, are 65 connected with the primary windings 144, 145 and 146 of step-down single-phase transformers 147, 148 and 149, respectively.

70 The secondary winding 150 of the transformer 147 supplies current to the electrodes 50, 50^a, 70 50^b, 51, 51^a and 51^b, and 54 to 59, inclusive, of tank 18' through single-phase transformers 151 and 152 as described of the supplying of current from the transformer 90 of Fig. 9 to the electrodes of tank 18 as shown in said figure and 75

as above described. Current is also supplied from the secondary 153 of the transformer 148 and the secondary 154 of the transformer 149 through step-down transformers 155 and 156, and 157 and 158, respectively, to the electrodes 50, 50^a, 50^b, 51, 51^a, and 51^b, and 54 to 59, inclusive, of the respective tanks 19' and 20', as explained above of the supplying of current through the transformers 147, 151 and 152 to the electrodes of tank 18'.

The use of a single tank in which the electrolytic pickling is effected is represented in Fig. 11 wherein the pickling tank represented at 18'' is provided with electrodes 50, 50^a, 50^b, 51, 51^a and 51^b, and 54 to 59, inclusive, as in the case of tank 18. In this arrangement the current for electrolytically pickling is shown as single phase alternating current supplied from any suitable source, the line current conductors being represented at 159 and 160 and connecting with the primary winding 161 of a step-down transformer 162. The secondary winding 163 of the transformer 162 supplies current to the electrodes 50, 50^a, 50^b, 51, 51^a, and 51^b, and 54 to 59, inclusive, through single-phase transformers 164 and 165 as described of the supplying of current from the transformer 99 of Fig. 9 to the electrodes of tank 18 as shown in said figure and as above described.

Referring to Fig. 12, which represents, by way of example, an arrangement whereby direct current is utilized to produce the electrolytic action, the pickling tanks therein shown are each represented, but without intention of restricting the invention thereto, as containing a pair of single electrodes 166 and 167 corresponding, respectively, to the six electrodes 50, 50^a, 50^b, 51, 51^a and 51^b and the six electrodes 54-59, inclusive, of the preceding figures of the drawings and spaced from the strip 16 as explained of the grouped electrodes above referred to.

The direct current for these two tanks which may be provided in multiples thereof, if desired, is shown as supplied from low-voltage high-amperage direct current generators 168 so connected, as shown, with the two sets of electrodes 166 and 167 that the flow of current between the electrodes in one of the tanks is in a direction opposite to the flow of current in the other tank, whereby the accelerated pickling action is effected first on one face of the strip 16 in its passage through the first tank, and then on its opposite face in its passage through the second tank, producing substantially uniform pickling of both faces of the strip.

The generators 168 may be driven in any suitable way, as for example by alternating current or direct current high voltage motors represented at 169.

In Figs. 13 and 14 I have shown my invention as utilized in the batch pickling of lengths of metal material less than that of the pickling tank, such as so-called sheets, supported on a suitable holder adapting the sheets to be lowered and raised in the tank, as for example by a crane.

In this particular construction the sheets to be pickled and represented at 170 are supported on edge on cross beams 171 forming the open bottom portion of a cradle represented generally at 172, the bars 171 being connected together by upwardly extending relatively widely spaced strips 173 as of wood, rising from the cross beams 171 and into the spaces between which the sheets 170, of less thickness than the width of these spaces, extend.

The structure formed of the cross beams 171 and spaced strips 173 is supported at the cross beams 171 on pairs of bars 174 carried by the lower T-heads 175 of links 176 pivotally connected at their upper ends to the ends of bars 177 carried by a spreader beam 178 having a cross pin 179 to be engaged by hoisting mechanism such as for example the hook 180 of a crane.

The cradle structure thus provided and such of the parts of which as may be made of metal being covered by current-insulating material, such as rubber, is adapted to be lowered for the complete immersion of the sheets 170 in the pickling bath contained in the tank represented at 181, the cradle structure resting at the cross bars 174 on spaced apart girders 182 provided on the bottom of the tank.

This construction as shown involves the use of stationary opposed plate electrodes located in the tank and completely submerged in the pickling bath and in spaced relation to the cradle, these electrodes, shown as in the form of plates, and which may extend substantially the full length of the tank either as single plates or in groups, as for example as explained above of the constructions in the preceding figures of the drawings, being represented at 183 and 184 and to which the desired electrolytic pickling current would be supplied. Such current may be either direct current or alternating current and may be supplied in any suitable way, as for example in accordance with the various electrical arrangements shown in the preceding figures of the drawings and described above. In the case of the use of direct current any suitable means may be provided for reversing the direction of flow of the current relative to the faces of the sheets 170. In the arrangement shown this may be effected by lifting the cradle and the sheets carried thereby clear of the tank after subjecting corresponding faces of the sheets to the electrolytic pickling action, and turning the cradle end for end through a half revolution and again lowering the cradle into the tank to subject the other corresponding faces of the sheets to the electrolytic pickling action.

As will be understood, the flow of current will be from one of the electrodes 183 and 184, thence through the bath to the nearest sheet and from the latter, through the bath, to the next sheet, and so on to the last sheet and thence from the bath to the other of the electrodes 183 and 184.

The feature of applying the electric current to the pickling bath without direct contact between the metal of the electrodes and the metal object to be pickled is of great advantage particularly in the case of the pickling of sheet material of relatively great width and of small cross section. To obtain effective electrolytic pickling action current density in the order of 100 amperes per square foot of surface of the sheet material to be pickled, is necessary, requiring, where the thin sheet material constitutes one of the electrodes, as in the case of prior practice, a great multitude of contacts at relatively close intervals along the length of the sheet material, otherwise the resistance of the sheet material is such that the electric current will leak off close to the contacts and considerable portions of the strip material will be unaffected by the electric current. By providing for the separation of the electrodes from the material to be pickled, as above referred to, the above disadvantage is avoided and the action of the electric current is such as to cause the sheet material to

be acted on substantially uniformly throughout the faces thereof exposed to the electrolytic action.

The use of alternating current to perform the electrolytic action is also of great advantage. Even when used under conditions in which one of the terminals of the alternating current circuit is electrically connected with the strip material (which would require an arrangement in which provision is made for causing the current to pass through the pickling bath to opposite faces of the sheets in succession, as by reversing the position of the electrode spaced from the sheet material so that for a sufficient length of time current would pass through the bath to one face of the sheet material to effectively pickle this face and then through the bath to the other face of the sheet material to effectually pickle it) the use of such current is of advantage as thereby great economies are effected in that the stationary transformer required in view of the large currents necessary, is much more economical of construction and more easily built, than a dynamo which is required when direct current is used.

The use of alternating current where the sheet material is run through the tanks in long strip form, as in the construction shown in Figs. 1-8, inclusive, or when relatively short length sheets are pickled in a batch operation as for example as shown in Figs. 13 and 14, and the metal of the electrodes is maintained out of contact with the material being pickled, presents the additional advantage in that the current flows into and away from the sides of the strip alternately, the variation depending upon the frequency used, and both sides of the sheet material are pickled equally effectively.

It may be stated by way of example, but without intending to thereby limit the invention in any way, that in the installation shown in Figs. 1 to 8, inclusive, each tank 18-21 may be approximately 60 feet long and the lower electrodes and the upper electrodes each of a total length of approximately 40 feet and where sheet material 48 inches wide is to be pickled the total area exposed between the electrodes may be approximately 160 square feet.

While I have illustrated and described certain particular constructions of apparatus embodying my invention and by which my novel method may be practiced, I do not wish to be understood as intending to limit it thereto as various changes and alterations may be made in the apparatuses shown, and the method practiced by other forms of apparatus (such as for example, provision made for simultaneously electrolytically pickling a plurality of the moving strips immersed in the pickling bath and flatwise opposed in spaced relation to each other between, and out of contact with, the metal of the electrodes between which the strips would travel, the current passing from one electrode through the bath to the strips in succession and thence to the other electrode) without departing from the spirit of my invention.

What I claim as new, and desire to secure by Letters Patent, is:

1. In electrolytic pickling apparatus, the combination of a tank containing a pickling bath, upper and lower electrodes, means for supporting sheet material to be pickled for movement through said bath and between, and out of electrical contact with, said electrodes, and means for adjusting the upper electrode into, and out of, immersed position in said bath, whereby the

sheet material may be raised out of contact with the bath.

2. In electrolytic pickling apparatus, the combination of tanks containing metal pickling baths and through which the objects to be pickled are passed in succession, means for producing electrolytic action in said baths comprising electrodes in contact with said baths, a 3-phase electric current supply, and means dividing the current from said supply and applying it to said electrodes, whereby the load on the circuit is balanced.

3. In electrolytic pickling apparatus, the combination of a tank containing a metal pickling bath, spaced apart electrodes of opposite polarity in contact with said bath and means for supporting strip material to be pickled for movement in the bath between, and out of electrical contact with, said electrodes, certain of said electrodes being formed of spaced apart sections in end to end relation.

4. In electrolytic pickling apparatus, the combination of a tank containing a metal pickling bath, spaced apart electrodes of opposite polarity in contact with said bath and means for supporting strip material to be pickled for movement in the bath between, and out of electrical contact with, said electrodes, each of said electrodes being formed of spaced apart sections in end to end relation.

5. In electrolytic pickling apparatus, the combination of a tank containing a metal pickling bath, spaced apart electrodes of opposite polarity in contact with said bath and means for supporting strip material to be pickled for movement in the bath between, and out of electrical contact with, said electrodes, certain of said electrodes being formed of spaced apart sections in end to end relation and of the same polarity.

6. In electrolytic pickling apparatus, the combination of a tank containing a metal pickling bath, spaced apart electrodes of opposite polarity in contact with said bath and means for supporting strip material to be pickled for movement in the bath between, and out of electrical contact with, said electrodes, both of said electrodes being formed of sections spaced apart in end to end relation lengthwise of the tank.

7. In electrolytic pickling apparatus, the combination of a tank containing a metal pickling bath, spaced apart electrodes in contact with said bath and means for supporting strip material to be pickled for movement in the bath between, and out of electrical contact with, said electrodes, certain of said electrodes being formed of spaced apart sections, certain of said electrodes opposing each other crosswise of the path of movement of the strip material and being of opposite polarity, whereby current traverses the strip crosswise thereof.

8. In electrolytic pickling apparatus, the combination of a tank containing a metal pickling bath, spaced apart electrodes in contact with said bath and means for supporting strip material to be pickled for movement in the bath between and out of electrical contact with, said electrodes, each of said electrodes being formed of spaced apart sections, certain of said electrodes opposing each other crosswise of the path of movement of the strip material and being of opposite polarity, whereby current traverses the strip crosswise thereof.

9. In electrolytic pickling apparatus, the combination of a tank containing a metal pickling bath, spaced apart electrodes in contact with said

- 5 bath and means for supporting strip material to be pickled for movement in the bath between, and out of electrical contact with, said electrodes, certain of said electrodes being formed of spaced apart sections of the same polarity, certain of said electrodes opposing each other crosswise of the path of movement of the strip material and being of opposite polarity, whereby current traverses the strip crosswise thereof.
- 10 10. In electrolytic pickling apparatus, the combination of a tank containing a metal pickling

bath, spaced apart electrodes in contact with said bath and means for supporting strip material to be pickled for movement in the bath between, and out of electrical contact with, said electrodes, both of said electrodes being formed of sections spaced apart lengthwise of the tank, certain of said electrodes opposing each other crosswise of the path of movement of the strip material and being of opposite polarity, whereby current traverses the strip crosswise thereof.

WILFRED SYKES.
